M. ZWICKY.

NARROWING SAFETY STOP FOR FULL FASHIONED KNITTING MACHINES.

APPLICATION FILED SEPT. 20, 1920.

1,381,444.

Patented June 14, 1921.

Melchior Zwickly Inventor

By his Attorney *M. Zwickly*

UNITED STATES PATENT OFFICE.

MELCHIOR ZWICKY, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

NARROWING SAFETY-STOP FOR FULL-FASHIONED KNITTING MACHINES.

1,381,444.

Specification of Letters Patent. Patented June 14, 1921.

Application filed September 20, 1920. Serial No. 411,362.

To all whom it may concern:

Be it known that I, MELCHIOR ZWICKY, a citizen of the United States, residing at Wyomissing, in the county of Berks and State of Pennsylvania, have invented certain new and useful Improvements in Narrowing Safety-Stop for Full-Fashioned Knitting-Machines, of which the following is a specification.

10 My invention relates to the narrowing mechanism of full-fashioned knitting machines; and it consists in providing in connection with usual pattern-controlled means for effecting the changes from knitting to narrowing operations, independent means for insuring desired continuance of the knitting operation against accidental changing such as is ordinarily liable to occur, as fully described in connection with the accompanying drawing and specifically pointed out in the claims.

Figure 1 is a partial front view of a full fashioned knitting machine having my invention applied thereto in preferred manner, directly coöperating parts only of the ordinary machine construction being indicated; and Fig. 2 is a cross-sectional view thereof. Fig. 3 is an enlarged detail view.

The narrowing nuts *a* and *b*, upon the reversely threaded narrowing screw *c*, are operated as usual in full fashioned knitting machines, to shift the narrowing points sidewise preliminary to transferring the loops; and the cam shaft *d* is provided with the usual shifting cams *e*, between which the roller *f* of the pivoted shifting lever *g* is swung to effect the lateral shifting of the cam shaft required for alternating the narrowing and knitting operations. The shifting lever *g*, as shown in the well known construction indicated, is normally pressed by a spring *h* so as to bring its roller *f* into operative contact with a shifting cam *e*, but is locked against such movement by a locking device *k* in engagement with a lever arm *g*¹ excepting when said device *k* is released as determined by the usual pattern chain; the lever *g* being returned to its locked position by the cam *e* after the narrowing operation is completed.

In the common construction thus briefly described, the pattern-controlled locking device *k* is relied upon to at all times maintain the shifting lever in inoperative position dur-

ing the ordinary knitting called for. A necessary incident of its required periodic operation however, is that it is liable to be accidentally released and thereby cause an unintended shifting to narrowing with damaging effects; and the purpose of my invention hereinafter described is to provide means for insuring against such harmful interruption of the intended regular knitting.

To this end I employ a special safety stop mechanism adapted to retain the shifting lever *g* in inoperative position, independently of the pattern-controlled locking device *k*, during regular knitting. As shown this special safety stop consists of a lever 10 pivoted intermediately to the frame of the machine at 11, and having the locking end 12 adapted to engage the shifting-cam roller *f* so as to prevent lateral movement of the latter; this locking end 12 being normally held in disengaged position however by the weighted opposite end 13 thereof, and being positively depressed into engagement when desired as follows:

Slidably mounted on the machine frame below the narrowing nuts is a stop-operating rod 15 provided with an adjustably fixed contact arm 16 extending into the path of the movable nuts and normally retracted against the nut *a* by a spring 17. The extended end 18 of this rod 15 is arranged to positively depress the locking end 12 of lever 10 into engagement with the shifting cam roller *f* when the narrowing nut *a* reaches the determined position indicated in Fig. 1; this being effected as shown by the cam-head end 18 of the rod 15 engaging the short end 20 of an interposed lever 21 carrying at its opposite end a connecting rod 22 pivotally connected to the safety-stop lever 10.

In operation, the shifting of the cam shaft *d* to effect desired movements of the narrowing nuts *a*, *b*, is effected as usual by automatically releasing the locking device *k* as determined by the pattern chain, the safety-stop 12 being held in inoperative position; but when this shifting is to be discontinued for uninterrupted regular knitting, the narrowing nut *a* will have moved the stop-operating rod 15 so as to throw the safety stop 12 into action as indicated in Fig. 2; so that thereafter no shifting of the cam shaft can be effected, even though the lock-

ing device *k* be accidentally thrown out, so long as the safety stop 12 is thus positioned. When the narrowing nuts are moved as usual after finishing the regular knitting, 5 the stop operating rod 15 and stop 12 are automatically withdrawn and so remain until the latter is automatically thrown in again as described. The mechanism specifically set forth may be readily modified with- 10 in the scope of the invention as defined in the claims.

What I claim is:

1. In a full fashioned knitting machine having narrowing nuts, a laterally shiftable cam shaft, and a shifting lever normally movable into operative relation to said cam shaft; a pattern-released locking device for said lever and a supplemental automatically operated safety lock therefor.
2. In a full fashioned knitting machine

having narrowing nuts, a laterally shiftable cam shaft, and a shifting lever normally movable into operative relation to said cam shaft; a pattern-released locking device for said lever and a supplemental safety lock 25 therefor controlled by the narrowing-nut movement.

3. In a full fashioned knitting machine having narrowing nuts, a cam shaft with shifting cams fixed thereto, and a cam- 30 roller shifting lever normally movable into operative relation to said shifting cams; a pattern-released locking device for said lever, and a separate roller-engaging locking lever with operating connections thereto 35 comprising a contact arm arranged in the narrowing-nut path.

In testimony whereof I affix my signature.

MELCHIOR ZWICKY.
